(57) **CLAIM**

We claim the ornamental design for a sensor assembly for a vehicle door, as shown and described.

DESCRIPTION

FIG. 1 is a top right perspective view of the sensor assembly for a vehicle door;

FIG. 2 is a top left perspective view thereof;

FIG. 3 is a bottom left perspective view thereof;

FIG. 4 is a bottom right perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is a top left perspective view of an alternative embodiment of the sensor assembly for a vehicle door.

The second embodiment is a mirror image of sensor assembly for a vehicle door as shown in FIGS. 1-10.

In the drawings, the broken lines depict portions of the design that form no part of the claim.
